(57) **CLAIM**

The ornamental design for a firearm suppressor assembly, as shown and described.

DESCRIPTION

FIG. 1 is a top, front, right perspective view of a firearm suppressor assembly in accordance with our new design; FIG. 2 is a top, rear, left perspective view thereof; FIG. 3 is a top view thereof; FIG. 4 is a bottom view thereof; FIG. 5 is a front view thereof; FIG. 6 is a rear view thereof; FIG. 7 is a left side view thereof; FIG. 8 is a right side view thereof; FIG. 9 is a top, front, left perspective view thereof; FIG. 10 is a bottom, rear, right perspective view thereof; FIG. 11 is a top, rear, right perspective view thereof; FIG. 12 is a vertical section of FIG. 1, along line 12-12; FIG. 13 is a horizontal section of FIG. 1, along line 13-13; FIG. 14 is a top, front, right perspective view of a first component of the firearm suppressor assembly of FIG. 1, the first component being a firearm suppressor tube; FIG. 15 is a top, rear, left perspective view of the first component thereof; FIG. 16 is a top view of the first component thereof; FIG. 17 is a bottom view of the first component thereof; FIG. 18 is a front view of the first component thereof; FIG. 19 is a rear view of the first component thereof; FIG. 20 is a left side view of the first component thereof; FIG. 21 is a right side view of the first component thereof; FIG. 22 is a top, front, left perspective view of the first component thereof;

(Continued)

FIG. 23 is a bottom, rear, right perspective view of the first component thereof;
 FIG. 24 is a top, rear, right perspective view of the first component thereof;
 FIG. 25 is a vertical section of FIG. 14, along line 25-25;
 FIG. 26 is a top, front, right perspective view of a second component of the firearm suppressor assembly of FIG. 1, the second component being a firearm suppressor core;
 FIG. 27 is a top, rear, left perspective view of the second component thereof;
 FIG. 28 is a top view of the second component thereof;
 FIG. 29 is a bottom view of the second component thereof;
 FIG. 30 is a front view of the second component thereof;
 FIG. 31 is a rear view of the second component thereof;
 FIG. 32 is a left side view of the second component thereof;
 FIG. 33 is a right side view of the second component thereof;
 FIG. 34 is a top, front, left perspective view of the second component thereof;
 FIG. 35 is a bottom, rear, right perspective view of the second component thereof;
 FIG. 36 is a top, rear, right perspective view of the second component thereof;
 FIG. 37 is a vertical section of FIG. 26, along line 37-37;
 FIG. 38 is a horizontal section of FIG. 26, along line 38-38;
 FIG. 39 is a vertical section of FIG. 32, along line 39-39;
 FIG. 40 is a vertical section of FIG. 32, along line 40-40;
 FIG. 41 is a vertical section of FIG. 32, along line 41-41;
 FIG. 42 is a vertical section of FIG. 32, along line 42-42;
 FIG. 43 is a top, front, right perspective view of a third component of the firearm suppressor assembly of FIG. 1, the third component being a firearm suppressor mount body base;
 FIG. 44 is a top, rear, left perspective view of the third component thereof;
 FIG. 45 is a top view of the third component thereof;
 FIG. 46 is a bottom view of the third component thereof;
 FIG. 47 is a front view of the third component thereof;
 FIG. 48 is a rear view of the third component thereof;
 FIG. 49 is a left side view of the third component thereof;
 FIG. 50 is a right side view of the third component thereof;
 FIG. 51 is a top, rear, right perspective view of the third component thereof;
 FIG. 52 is a vertical section of FIG. 43, along line 52-52;
 FIG. 53 is a top, front, right perspective view of a fourth component of the firearm suppressor assembly of FIG. 1, the fourth component being a firearm suppressor mount body spring;
 FIG. 54 is a top, rear, left perspective view of the fourth component thereof;
 FIG. 55 is a top view of the fourth component thereof;
 FIG. 56 is a bottom view of the fourth component thereof;
 FIG. 57 is a front view of the fourth component thereof;
 FIG. 58 is a rear view of the fourth component thereof;
 FIG. 59 is a left side view of the fourth component thereof;

FIG. 60 is a right side view of the fourth component thereof;
 FIG. 61 is a top, rear, right perspective view of the fourth component thereof;
 FIG. 62 is a top, front, right perspective view of a fifth component of the firearm suppressor assembly of FIG. 1, the fifth component being a firearm suppressor modular mount;
 FIG. 63 is a top, rear, left perspective view of the fifth component thereof;
 FIG. 64 is a top view of the fifth component thereof;
 FIG. 65 is a bottom view of the fifth component thereof;
 FIG. 66 is a front view of the fifth component thereof;
 FIG. 67 is a rear view of the fifth component thereof;
 FIG. 68 is a left side view of the fifth component thereof;
 FIG. 69 is a right side view of the fifth component thereof;
 FIG. 70 is a top, rear, right perspective view of the fifth component thereof;
 FIG. 71 is a vertical section of FIG. 62, along line 71-71;
 FIG. 72 shows top, rear, right perspective views of the components of FIGS. 14-71, in an exploded configuration; and,
 FIG. 73 shows top, rear, right perspective views of the components of FIGS. 14-71, in an exploded configuration. The broken lines in FIG. 73 are for the purpose of illustrating the relative orientation of the components of FIGS. 14-71 and form no part of the claimed design.
